UNITED STATES PATENT OFFICE.

ANDREW L. WHEELER, OF ROCKFORD, ILLINOIS.

STEAM-BOILER.

SPECIFICATION forming part of Letters Patent No. 359,699, dated March 22, 1887.

Application filed September 21, 1886. Serial No. 214,170. (No model.)

To all whom it may concern:

Be it known that I, ANDREW L. WHEELER, a citizen of the United States, residing in the city of Rockford, in the county of Winnebago 5 and State of Illinois, have invented a new and useful Improvement in Steam-Boilers, of which the following is a specification.

This invention relates to steam-boilers, but more especially to boiler ends, and when employed in locomotive-boilers will constitute the forward end of the boiler. Its object is to produce a boiler end with removable center, having a self-locking construction, a hinge-connection with main portion of the end, and 15 a nut-lock to prevent accidental displacement. To this end I have designed and constructed the boiler end represented in the accompanying drawings, in which—

Figure 1 is an outer face isometrical representation of a boiler end embodying my invention. Fig. 2 is an inner isometrical face view of the boiler end; and Fig. 3 is a central section on dotted line *a*, Fig. 2.

The main or outer portion of the boiler end 25 is of the usual construction, consisting of the outer disk-ring portion, 1, and the inner raised-ring portion, 2, in this instance of ogee or cyma-recta form in section, forming the surrounding wall of its center opening. The inner edge of the wall forming the center opening is formed in equal divisions, with like inclined portions, 3, and between these like inclined portions like openings, 4, are formed, about equal in depth to the depth of the inclines in the plane of the central opening. A 35 cap, 5, preferably of concavo-convex form and of sufficient dimensions, is employed to cover the central opening. The outer or annular edge of the cap 4 is rabbeted to enter within 40 the inward-projecting inclines 3. Clasp-arms 6 rise at proper intervals from the inner face of the cap, and their outer ends project outward over the rabbeted portion of the cap, and are fitted to overlap the like inclined portions 45 3 on the inner edge of the center openings. The position of the clasp-arms on the cap are such as to coincide with the like openings 4 between the like inclined portions projecting from the inner edge of the center opening, and 50 their dimensions are such as to enter the openings freely.

The construction and arrangement of these

parts are such that in putting the cap in place the clasp-arms will freely enter the openings between the inclined portions, and a partial turn of the cap in the direction of the arrow on Fig. 1 will cause the clasp-arms to engage the like inclined portions and rise on their inclined surfaces, and cause the cap to engage the annular outer surface of the opening firmly 55 and hold the parts securely in place, and capable of being readily removed by rotating the cap in the direction opposite that indicated by the arrow thereon. A prominence, 7, rises from the outer surface of the cap, and is provided with a radial hole, 8, to receive a bar or lever, to serve as a wrench to turn the cap to fix it in place on the boiler end or disengage it therefrom. A forked hinge-bar, 9, is hinge-jointed to the end proper by means of 60 ears 10, rising therefrom, and a joint-rod, 11, connecting the forked ends of the bar with the ears. An axle-joint bolt, 12, either fixed in the axial center of the cap or passed outward through its axial center, projects from the cap 65 and receives the end portion of the forked hinge-bar 9, and forms a pivoted connection of the cap with the hinge-bar, to permit it to turn on its pivotal connection therewith. A screw-nut, 13, on the projecting end of the pivot-bolt 70 serves as a lock-nut to fix the parts, when in place, to prevent accidental displacement, and a slackening of the screw-nut 13 will permit the removal of the cap and still hold it in its hinged connection with the boiler end. A number-plate, 14, to contain the numerals indicating the number of the boiler or the machine of 75 which it is a part, is fixed in place on bracket-arms 15, rising from the axial end of the forked hinge-bar.

I claim as my invention—

1. The combination, with the main portion of the boiler end, and with the removable cap having a self-locking connection, of a hinged bar having a hinged connection with the main portion of the end, and connected to the cap by a bolt upon which the cap is adapted to rotate, and means for locking the nut-connection to prevent the aforesaid rotation of the cap, substantially as set forth.

2. The combination, with the main portion of the boiler end having inclined portions projecting from the inner edge of its center opening, of a cap for said opening, and provided with

projecting clasp-arms to engage the inclined projections, a hinged bar having a hinged connection with the main portion of the end and connected to the cap by a bolt upon which the cap is adapted to rotate, and means for locking the nut-connection to prevent the aforesaid rotation, substantially as set forth.

3. The combination, with the main portion of the boiler end, and with the removable cap having a self-locking connection and a hinged bar having a hinged connection with the main portion of the end, and connected to the cap by

a bolt upon which the cap is adapted to rotate, of means for locking the nut-connection to prevent the aforesaid rotation, and a number-plate supported upon the inner end portion of the hinged bar, so as to cover the bolt-connection and locking means, substantially as set forth. 15

ANDREW L. WHEELER.
